UNITED STATES PATENT OFFICE

EDWARD E. EVANS, OF ST. LOUIS, MISSOURI

COMBINED STREET INDICATOR AND TRAVELING SIGN SYSTEM FOR CARS

Application filed January 6, 1930. Serial No. 418,780.

This invention is a combined street indicator and traveling sign system for street cars or other vehicles.

One object of the invention is to provide in combination, in relatively simple, compact and efficient form, means for both indicating or showing to passengers the names of the successive streets as the vehicle approaches them, and means for simultaneously displaying to the passengers a plurality of signs arranged to travel upon a suitably mounted endless belt.

Another object is to provide for the sides of the car horizontally traveling belts operable by any suitable means as by an electric motor, upon which belts signs or advertising matter, or any other desired data may be displayed, cooperatively combined with a street indicating belt or tape mounted at the front of the car and adapted to travel in a vertical manner over vertically spaced rollers, the last named or street belt having represented thereupon the names of the streets in regular order as they will be crossed by the car in its journey.

Another object is to provide for a street car or the like cooperating horizontally traveling advertising belts for the sides of the car and a vertically traveling street belt for the front of the car, the former moving constantly and the latter moving intermittently as street intersections are approached, the said intermittent action of the sign belt being accomplished through an electric clutch mechanism operable by the driver and through which the sign belt mechanism is momentarily connected with and actuated by the sign belt mechanism, for the purpose of successively showing the names of the streets as the same are approached or arrived at by the car.

Another object is to provide cooperating traveling belts, one moving constantly along the side of the car and the other moving intermittently at the front of the car through the intermittent connection of the two, and both belts being adapted to draw or attract joint attention or interest upon the part of the passengers in the car.

Still another object is to provide for the

two belt systems referred to a solenoidal clutch placed under the control of the driver of the car, whereby the required intermittent connection of the two belt systems may be readily brought about.

55

In the drawings

Figure 1 shows the street belt system in elevation (the housing thereof being shown in section), in combination with the advertising belt system at the right, (the belt itself being shown in section);

60

Figure 2 is an enlarged detail, partly in section of the clutch mechanism;

65

Figure 3 is a section on the line 3-3 of Figure 2;

65

Figure 4 is a section on the line 4-4 of Figure 1;

70

Figure 5 is an elevation of the advertising or sign belt and supporting rollers, a medial section of the belt being broken away.

In carrying out this invention, an endless advertising belt 1 is provided and mounted over rollers 2 angularly disposed at each end of a side of a street car 3, the said rollers having the shafts 4 journaled at their ends in brackets 5 fastened to the upper portions of the side of the car as shown at 6. The roller at the forward end of the car is provided at each end with rigidly mounted beveled gears 7 and through which the shaft 4 is passed. Upon this belt may be displayed any signs, advertising matter or other data desired, the same being carried around the rollers and traveling from end to end of the car with the belt. At the front of the car are arranged two vertically spaced rollers 8 rigidly set upon shafts 9 journaled within the housing 10 which is suitably secured in place upon the car. A street name belt, tape or ribbon 11 is carried by these rollers 8, to which the ends of the said belt are secured, the said belt being thus adapted to roll up alternately on either of the rollers. The names of the several cross streets which are regularly crossed by the car in its routine trips are represented in order upon the said street belt, as indicated at 12 in Figure 1. The roller shafts 9 are journaled within the housing 10 in any convenient manner. As here shown the two left hand ends are journaled in the left hand side of the hous-

ing as shown at 13, while the right hand ends are journaled in brackets 14 extended from the back of the housing. Between these ends of the shafts and the adjacent end of the housing are mounted two solenoids 15 which are adapted to be electrically energized through conductors 16 running to any source of electrical energy (not shown). These solenoids are aligned with the shafts 9 and the adjacent ends of the shafts are cut out to form square sockets 17. Drive shafts 18 are journaled in alignment with the solenoids 15 and the beveled gears 7 of the forward roller 2, the outer ends of the said shafts having rigidly mounted beveled gears 19 placed in mesh with the gears 7. The opposite ends of the shafts 18 have the deep and square sockets 20 formed therein similar to the sockets 17, these shaft ends being disposed immediately adjacent the ends of the solenoids. Square plunger 21 of a size adapted freely to engage at their ends the squared sockets 17 and 20 are slidably mounted through the solenoids 15, and have their outer ends inserted within the deep sockets 20 of the drive shafts, where they are slidably held in place by means of retractile springs 22 which have their ends anchored to the ends of the plungers and the inner end walls of the sockets. The plungers are thus adapted to rotate with the shafts 18 within the solenoids 15 and to reciprocate within the solenoids and the sockets 20. The free ends of the plungers 21 are disposed immediately adjacent the outer ends of the sockets 17 of the shafts 9 and are normally held out of engagement with said sockets by the springs 22. However, upon the energization of the solenoids 15, the said plungers may be drawn out and thrust into engagement with the sockets 17 and thereupon the shafts 9 would, of course, rotate with the shafts 18. The geared roller 2 is driven constantly in any conventional manner, as by the electric motor 23 fastened to the front of the car. The speed of the roller is reduced as desired through a train of reduction gearing 24. Switches 25 are interposed in the electric lines 16, and these switches are placed at the hand of the driver of the car.

In operation the advertising bolt 1 travels continuously, being driven by the motor 23. Upon approaching the cross streets in order, the driver, conductor or motorman, as desired, operates the required one of the switches 25 to cause the travel of the street belt 11 so as to bring the required street name into view. In the travel of the car in one direction upon its trip, the proper switch would be operated to roll the belt 11 upon say the upper one of the rollers 8, and upon the return trip the other switch would be operated so as to roll the belt back again upon the lower roller 8. Thus the constantly rotating geared shaft 4 of the advertising belt mechanism serves to impart intermittent rotation to the shafts 9 of the street

name mechanism, as desired. The operation of the street name belt 11 attracts the attention of the passengers, which causes them in turn to notice signs upon the advertising belt 1 and thus the two systems cooperate for attracting the attention of passengers to each. 70

While I have herein described a certain specific manner and method of constructing and assembling the elements of my invention, it is understood that I may vary from the same in minor details, not departing from the spirit of my invention, so as best to construct a practical device for the purpose intended, as defined in the appended claims. 75

I claim:

1. In a device of the kind described for a street car or the like, the combination of a constantly traveling advertising belt, mechanism to operate the same, an intermittently traveling street name belt, mechanism to operate the same, the mechanism of the latter being adapted to be actuated by the mechanism of the former. 80

2. In a device of the kind described for a street car or the like, the combination of a horizontally mounted and constantly traveling advertising belt, mechanism to operate the same, a vertically mounted street name belt, mechanism to operate the same, and means for intermittently connecting the two mechanisms to cause their conjoint operation. 85

3. In a device of the kind described for a street car or the like, in combination, rollers mounted at the ends of the car in horizontal spaced relation, an endless advertising belt mounted over the rollers and adapted to travel horizontally from end to end of the car, rollers mounted at the front of the car in vertical spaced relation, a street name belt mounted upon said rollers with their ends attached thereto, means for driving the rollers of the advertising belt, and means for intermittently driving the rollers of the street name belt through connections extended to the driving means of the advertising belt. 100

4. In a device of the kind described for a street car or the like, in combination, a roller shaft journaled at the front end of the car, the said shaft being disposed out of the horizontal, gears upon the ends of the shaft, two drive shafts journaled horizontally at the front of the car in alignment with the gears of the said roller shaft, gears upon the ends of the said drive shafts in mesh with the gears of the roller shaft, the free ends of the drive shafts having deep and squared sockets formed therein, two driven shafts journaled horizontally at the front of the car in alignment with and spaced from the said drive shafts, the ends of the driven shafts adjacent the drive shafts having squared sockets similar to the sockets of the drive shafts, solenoids mounted between the ends of the drive and driven shafts, plungers squared at their ends and mounted within the said solenoids, 110

the ends of the plungers at one side being extended freely within the sockets of the drive shafts and the ends at the opposite side being disposed immediately adjacent the sockets of the driven shafts, means for normally holding the said plungers retracted within the sockets of the drive shafts, and intermittently operable means for electrically energizing the solenoids for drawing the said plungers into engagement with the sockets of the driven shafts.

In testimony whereof I affix my signature.
EDWARD E. EVANS.
